UNITED STATES PATENT OFFICE.

ALBERT M. BULLARD, OF NEW YORK, N. Y., ASSIGNOR, BY MESNE ASSIGNMENTS, TO
WESTERN ELECTRIC COMPANY, INCORPORATED, A CORPORATION OF NEW YORK.

SEMIMECHANICAL TELEPHONE SYSTEM.

1,334,077.

Specification of Letters Patent. Patented Mar. 16, 1920.

Application filed February 5, 1907, Serial No. 355,897. Renewed November 8, 1909. Serial No. 526,890.

To all whom it may concern:

Be it known that I, ALBERT M. BULLARD, citizen of the United States, residing at New York, in the county of New York and State 5 of New York, have invented a certain new and useful Improvement in Semimechanical Telephone Systems, of which the following is a full, clear, concise, and exact description.

This invention relates to improved rever- 10 tive call indicating means for telephone ex- change systems having party lines. In such a system it frequently occurs that a sub- scriber at one of the substations of a party line desires to communicate with a subscriber 15 at another station of the same line. The ordinary busy test in such a case will give a false busy indication because a test guard has been placed upon the multiple terminal 20 of the line, by reason of the use of that line in calling and not because it is already en- gaged by some other subscriber. It is not 25 desirable, however, that under ordinary traf- fic conditions, either the calling subscriber or the operator should be required to know from the mere number of the called station 30 whether it is on the same party line as the calling station.

It is the purpose, therefore, of this invention to provide improved means for giving a 35 special signal in all cases of such revertive calls, that is, where the terminal of the called line which is tested, is merely a multiple terminal of the calling line. A signal device is associated with the originating or 40 answering end of the connecting circuit which is united with any calling line in re- sponse to a call, and one terminal of said 45 signaling device is arranged to be connected thereby to a conductor of the calling line 45 which extends to contacts at all of the multiple terminals of such line. Switching ap- 50 paratus associated with the other end of the connecting circuit is adapted to connect the other terminal of said signal device to a multiple terminal of a conductor corre- 55 sponding to the conductor to which the signal device is connected at the originating or answering end of the connecting circuit, so that where the terminal with which contact is made is a multiple terminal of the calling line, the circuit of said signal device will be completed and the signal given to indicate that the call is a revertive one.

Preferably the special signal apparatus 55 is brought into operative relation with the

connecting circuit and the signal device connected to a conductor of the calling line only momentarily at the time when the switching apparatus is testing the terminal of the called line; at this same time the usual 60 test guard upon the test conductor of the calling line may be removed, such test guard being otherwise maintained at all multiple terminals of the line during the entire period of connection therewith. 65

This invention will be of especial utility in connection with semi-automatic systems of the type in which the calls are answered by an operator and connection completed to the called line by means of automatic switch- 70 ing mechanism controlled by the operator, as shown for example in Patent 1,161,608 of November 23, 1915, to A. M. Bullard.

The invention is illustrated by the accompanying drawing in its application to 75 such a system. Only the circuits and apparatus which are directly concerned with the invention are illustrated, however.

In the drawings, 1, 2 and 3 represent re- 80 spectively the tip, ring and sleeve of an op- erator's answering plug, while 4, 5 and 6 show the corresponding answering jack ter- minals of a subscriber's line 7. This sub- 85 scriber's line 7 is a party telephone line of usual construction and arrangement, com- prising conductors 8 and 9, having connect- 90 ed therewith through the contacts of the usual cut-off relay 10 associated therewith the usual line relay 11 and source of current 12. One terminal of the cut-off relay 10 is 95 connected, as is customary, with the test con- ductor and the sleeve contact individual to the line 7, and the other terminal of such cut-off relay is connected, as is also usual, to the grounded battery 13. The line 7 is pro- 100 vided also with multiple contacts 14, 15 and 16, connected, respectively, by the conductors 17, 18 and 19 to the tip, ring and sleeve contacts 4, 5 and 6 of the answering jack of such line. These multiple contacts, of which only one set are shown, are indicated upon the right hand side of the drawing, but it will be understood that there may be as many sets of these multiple contacts as may be de- 105 sirable.

When a subscriber upon the line 7, which, as above noted, is assumed to be a party telephone line, desires connection with another party on the same line, the attention of the operator is attracted in the usual way. 110

The operator thereupon inserts the plug 20 in the jack 21 in order to receive a call. Immediately upon the insertion of this plug, which has brought the tip, ring and sleeve contacts 1, 2 and 3, respectively, into contact with the corresponding contacts 4, 5 and 6, respectively, a test guard is placed upon the test conductor 19 of the calling line by means of a low resistance circuit to ground, extending from the sleeve contact 6 of the answering jack 21, through the sleeve 3 of the plug 20, conductor 22, conductor 23, back contact and armature 24 of the relay 25, to be hereinafter referred to, conductor 26, sleeve relay 27 to ground. This provides a path for current from the battery 13, which operates the cut-off relay 10 and the sleeve relay 27 in the usual manner and lowers the normal potential upon the sleeve or test contact 6 of the answering jack and also upon the test contact 16 of the multiple contacts. It may here be noted that a circuit to maintain the sleeve relay 27 energized after its initial energization, is provided in parallel of the armature 24 and its back contact through the high resistance 28, which circuit, however, when the armature 24 has been attracted by the relay 25 and has opened shunt around the high resistance 28, is of too high resistance to sufficiently lower the potential of the sleeve or test contact 6 and the connected multiple test contacts 16 to make such contacts test busy.

The operator having learned from the calling subscriber the number of the desired party causes the automatic switching device 29 shown in detail in Fig. 4 of said patent, at which the multiple contacts 14, 15, 16 appear, to bring its contact brushes 30, 31, 32 by means of a sender such, for example, as that shown in Figs. 5, 6 and 7 of said patent, into contact with the multiple terminals 14, 15, 16 of the line on which the desired party is located. When this automatic switching device has made its final selective movement and the contact brushes 30, 31, 32 are in contact with the multiple terminals 14, 15, 16 of the desired line, the switch 33 is arranged to be operated automatically the instant the connector reaches the terminals of the desired line. This contact 33 corresponds to the armature 32 and front contact of relay 33 of Fig. 5 of said patent. The relay 33 is operated automatically by the sender at the termination of units selection. This part of the operation of the system of said patent is described in detail on page 15, lines 15 to 82 inclusive and page 22, lines 7 to 52 inclusive.

60 The energization of the relay 25, which corresponds to relay 491 of said patent, due to the closure of the circuit through the switch 33, will attract its various armatures. The attraction of the armature 24 will open 65 the shunt around the high resistance 28 and

in so doing will remove the test guard from the sleeve contact 6 of the jack 21 and from the associated multiple contacts 16, so that the automatic switching device 29 in testing the line will find it unguarded and apparently in idle condition, the circuit through the high resistance 28 and the sleeve relay 27 being, as has been before noted, of too high resistance to reduce appreciably the potential of the sleeve contact 6 from its 70 normal or idle potential, due to the connection of the battery 13. Sufficient current, however, will continue to pass from the battery 13 through the cut-off relay 10 and the sleeve relay 27 to maintain the sleeve relay 80 27 energized. The attraction of the armatures 35 and 36 has opened at their back contacts the normal ground connections of the tip conductors 37 and 38 of the connecting circuit and at the same time has through 85 their front contacts included in the circuit of the tip conductors 37 and 38, a source of current 39 and a winding 40 of the relay 41. This source of current 39 may be of any desired character, but is preferably, as shown, 90 the secondary winding of an induction coil 42, the primary winding 43 of which is in circuit with the constantly operating source of pulsating or alternating current 44.

Assuming now that at the time the relay 95 25 is energized, the brushes 30, 31 and 32 of the automatic switching device 29 are in contact with the multiple terminals of the calling line, that is, the line with which the plug 20 is connected through the jack 21, 100 a circuit will be established from the source of alternating current 39 through the armature 36 and its front contact, conductor 45, tip conductor 37 of the originating end of the connecting circuit, tip contact 1 of the 105 plug 20, corresponding contact 4 of the jack 21, conductor 17, multiple contact 14, brush 30 of the automatic switching device 29, tip conductor 38 of the connecting circuit, conductor 46, armature 35 and its front 110 contact, conductor 47, winding 40 of the relay 41, and back to the source of alternating current 39. This will cause the energization of the relay 41, which will attract its armatures, and in so doing will establish for 115 itself a locking circuit from the battery 48, armature 49 and its front contact of the relay 27, which relay, it will be remembered, remains energized by current from the battery 13, conductor 50, conductor 51, armature 52 and its front contact, winding 53 of the relay 41 and ground back to battery. The attraction of the armature 54 by the 120 relay 41 has opened the normally closed connection through the armature 54 and its back contact of the ring conductor 55 of the connecting circuit, and has closed a circuit from the battery 56 through the supervisory relay 57, ring conductor 58, armature 54 and its front contact, conductor 59 125 pulsator 59 130

to ground and back to battery. The making and breaking of this circuit by the pulsator 59 will cause the corresponding energization and deenergization of the supervisory relay 57, which will in turn cause a corresponding flashing of the supervisory lamp 60. The current for this lamp is supplied from battery 48 through the armature 49 and its front contact of the relay 27, conductor 50, armature 61 and its back contact of the supervisory relay 57, supervisory lamp 60 and thence to ground and back to battery. The relay 41 having once been energized by the momentary closure of the circuit through the winding 40 will remain locked in energized condition by current through the winding 53 so long as the relay 27 is energized. It will therefore be seen that if the call over the line 7 is a revertive one, the momentary energization of the relay 25 will, in the first place, remove the test guard from the multiple contact 16 of the calling line, in order that the automatic switching apparatus will not find a test guard upon the terminal 16, and, in the second place, will cause a distinctive signal to be displayed before the operator, which distinctive signal will continue until the operator removes the plug from the jack 21 and thereby opens the intermittently closed circuit through the pulsator 59 and the supervisory relay 57. The distinctive signal referred to is obviously the intermittent flashing of the supervisory lamp which has been hereinbefore described.

The operator, having had brought to her attention the fact that the call is a revertive one, may proceed in any suitable way and by any suitable means to ring the desired party upon the calling line 7, but since this forms no part of the present invention, no means for accomplishing this result need be shown, the only necessary act to accomplish the restoration of the apparatus to normal, so far as relates to this invention, being the removal of the plug 20 from the jack 21 in order to deenergize the relays 27 and 41, which removal will necessarily occur in the ordinary operation of a system of this character and may be either before or after the ringing of the desired party.

If, however, at the time that the switch 33 is momentarily closed, as before described, the brushes 30, 31, 32 of the automatic switching apparatus 29 were in connection with the multiple test terminals of some line other than the calling line, the circuit from the source of alternating current 39, including the winding 40 of the relay 41 and the armatures 35 and 36 and their front contacts of the relay 25, will not be completed since the brush 30 of the automatic switching apparatus 29 is not in contact with the multiple terminal of the calling line, and no circuit will therefore be

established from the tip contact 1 of the plug 20 through the corresponding contact 4 of the jack 21, conductor 17 and the multiple contact 14 of the calling line to the brush 30. The relay 41 will therefore remain unenergized and the flashing of the supervisory lamp 60, as above described, will not occur. The operator therefore will know that the call is not a revertive one and will not perform any special acts in connection therewith, but will allow connection to be established in the way usual to such systems.

It may here be noted that during the establishment of each connection, the test guard is momentarily removed from the calling line, whether or no the call be a revertive one, but such removal of the test guard being only momentary, will not detrimentally affect the proper operation of the system.

The connecting circuit, which is only diagrammatically shown, since it in itself forms no part of this invention, comprises, as is usual, in addition to the parts already described, a supervisory relay 62 included in the ring conductor 63 of the originating or answering end of the connecting circuit and the usual repeating coil windings 64, 65, 66 and 67, inserted, respectively, in the conductors 37, 38, 63 and 55. The automatic switching device 29 and its associated test circuit 68 and test relay 69 are shown only so far as they are necessary for a full and definite understanding of this invention, and it will of course be understood that they may be of any ordinary or usual construction that may be desired.

It will therefore be seen that in the operation of a system involving this invention, if the call is a revertive one, the automatic switching apparatus will be allowed to seize the calling line at its multiple contacts in such switching apparatus in spite of the normal application of the test guard at the originating end of the connecting circuit, and furthermore that a distinctive signal will be displayed indicating that the call is a revertive one. On the other hand, if the call is not a revertive call, the ordinary or normal operation of the system is in no way interfered with or changed, and no unnecessary burden is at any time placed upon the operator or upon the calling subscriber in order to accomplish the proper connection in a revertive call.

It should be understood that in all cases where the "originating" end of the connecting circuit is referred to, either in the specification or claims, that end of the connecting circuit is meant which corresponds to the answering end of an operator's cord circuit in a manual system, whether such "connecting circuit" be means for interconnecting subscribers' lines in an automatic, semi-

automatic or manual system. It should be further understood that while this invention is shown as applied to a semi-automatic telephone exchange system and is of especial utility in connection with such a system, it is also well adapted for use either in connection with a "full automatic" telephone exchange system, or a "manual" telephone exchange system, and it is not to be 10 considered as limited to a semi-automatic system any further than the claims herein after appended may indicate.

It should be further understood that while there are shown various and independent 15 batteries in connection with the disclosure of the invention, where these batteries are of the same polarity and potential, and are located in the same exchange, they may be and preferably are one and the same battery.

20 Having described my invention what I claim and desire to secure by Letters Patent of the United States is:

1. In a telephone exchange system, the combination with a party telephone line having multiple terminals, of a connecting circuit adapted to be united therewith, a revertive signal, a controlling relay therefor, associated with the originating end of said connecting circuit, and an operative 25 circuit for said relay completed only through multiple terminals of said party line at each end of said connecting circuit.

2. In a telephone exchange system, the combination with a party telephone line having multiple terminals, of a connecting circuit adapted to be connected therewith, a revertive signal, a controlling relay therefor, associated with the originating end of said connecting circuit, and an operative 30 circuit for said relay completed only through a talking conductor and multiple terminals of said party line at each end of said connecting circuit.

3. In a telephone exchange system, the combination with a party telephone line having multiple terminals, of a connecting circuit adapted to be united therewith, a signal device associated with said connecting circuit, and a circuit for said device including corresponding terminals of said connecting circuit at each end thereof and multiple terminals of said party line.

4. In a telephone exchange system, the combination with a party telephone line having multiple terminals, of a connecting circuit adapted to be united therewith, a signal device associated with said connecting circuit, and a circuit for said device including corresponding terminals of said connecting circuit at each end thereof and multiple terminals of said party line.

5. In a telephone exchange system, the combination with a party telephone line having multiple terminals, of a connecting 60 circuit adapted to be united therewith, a

revertive signal device, a relay controlling the same associated with the originating end of said connecting circuit, an operative circuit for said relay completed only through multiple terminals of said party line at each 70 end of said connecting circuit, and a switch in said connecting circuit momentarily operated to close the circuit of said relay, whereby said relay will be operated by the closure of said switch only when said connecting circuit is connected at both ends to the same line.

6. In a telephone exchange system, the combination with a party telephone line having multiple terminals, of a connecting 80 circuit adapted to be united with said terminals, a revertive signal, a controlling relay therefor, associated with the originating end of said connecting circuit, a circuit for said relay including a talking conductor 85 and multiple terminals of said party line at each end of said connecting circuit, and a switch in said connecting circuit momentarily operated to close the circuit of said relay, whereby said relay will be operated 90 by the closure of said switch only when said connecting circuit is connected at both ends with the same line.

7. In a telephone exchange system, the combination with a party telephone line 95 having multiple terminals, of a connecting circuit adapted to be united therewith, a signal device, a circuit for said signal device including said multiple terminals of said party line and corresponding terminals of said connecting circuit at each end thereof, and a switch in said circuit 100 momentarily operated to close a circuit of said signal device, whereby said signal device will be operated by the closure of said switch when said connecting circuit is connected at both ends to the same line.

8. In a telephone exchange system, the combination with a party telephone line, a connecting circuit, means for uniting said 110 connecting circuit with said party line, automatic switching apparatus adapted to unite said connecting circuit with a called telephone line, and a revertive call indicating signal automatically operated when said 115 switching mechanism makes connections with the calling line.

9. In a telephone exchange system, the combination with a party telephone line, of a connecting circuit, a connection switch 120 for uniting said connecting circuit to said line in response to a call, automatic switching apparatus for uniting said connecting circuit with other lines and a revertive call indicating signal automatically operated 125 when said automatic switching apparatus unites with the calling line in response to a call therefor.

10. In a telephone exchange system, the combination with a party telephone line 130

having multiple terminals, of a connecting circuit adapted to be united therewith terminating in an automatic switching device, one of said multiple terminals being located in said switching device, a signal device, a circuit for said signal device including contacts of said multiple terminals at both ends of said connecting circuit, and a switch for closing the circuit of said signal device, whereby said signal device will be operated by the closure of said switch when said automatic switching device is connected to a multiple terminal of the same line to which said connecting circuit is united at its originating end.

11. In a telephone exchange system, the combination with a party telephone line having multiple terminals, of a connecting circuit adapted to be united therewith terminating in an automatic switching device, one of said multiple terminals being located in said switching device, a signal device and a circuit for said signal device including contacts of said multiple terminals at both ends of said connecting circuit, and a switch for closing the circuit of said signal device, whereby said signal device will be operated upon the closure of said switch when said connecting circuit is in contact at both ends with the multiple terminals of the same line.

12. In a telephone exchange system, the combination with a party telephone line having multiple terminals, of a connecting circuit adapted to be united therewith terminating in an automatic switching device, one of said multiple terminals being located in said switching device, a signal device, a circuit for said signal device including a talking conductor and contacts of said multiple terminals at both ends of said connecting circuit, and a switch for closing the circuit of said signal device, whereby said signal device will be operated upon the closure of said switch when said connecting circuit is in contact at both ends with the multiple terminals of the same line.

13. In a telephone exchange system, the combination with a party telephone line having multiple terminals, some of said terminals being located upon automatic switching devices, an answering switch adapted to make contact with said line when calling, a signal device adapted to be associated with said calling line, an automatic switching device to which connection may be extended from said line, through said answering switch, said switching device having access to one of the multiple terminals of said line, and a circuit for said signal device including contacts of said answering switch and multiple contacts of said party line in said automatic switching device adapted to be completed when said

automatic switching device is in contact with the multiple terminals of the calling line.

14. In a telephone exchange system, the combination with a party telephone line, a connecting circuit, a connecting switch for uniting said connecting circuit with said line, automatic switching apparatus for uniting said connecting circuit with other lines, a supervisory signal associated with said connecting circuit, and means automatically actuated when said switching mechanism selects the calling line in response to a call for causing said supervisory signal to give a characteristic revertive call signal.

15. In a telephone exchange system, the combination with a party telephone line, of a connecting circuit, a manually operated connecting switch for uniting said connecting circuit with said line, automatic switching apparatus adapted to unite said connecting circuit with a desired line, a relay, a circuit for operating said relay adapted to be completed as the automatic switching apparatus is testing a called line, a supervisory signal associated with said connecting circuit, and means controlled by said relay in the test of the calling line in response to a call therefor to cause said supervisory signal to give a characteristic call signal.

16. In a telephone exchange system, the combination with a party telephone line, of a connecting circuit, a manually operated connecting switch for uniting said connecting circuit with said line, automatic switching apparatus adapted to unite said connecting circuit with other lines, a relay 25, a circuit therefor adapted to be completed while such automatic switching apparatus is testing the called line, a relay 41, a revertive call signal operated by said relay 41 when energized, and a circuit to operate said relay 41 completed by relay 25 when said automatic switching apparatus makes connection with the calling line.

17. In a telephone exchange system, the combination with a party telephone line, of a connecting circuit, a manually operated connecting switch for uniting said connecting circuit with a calling line, automatic switching apparatus adapted to unite said connecting circuit with the desired line, a relay 25, a circuit for operating same adapted to be completed as the automatic switching apparatus tests a called line, a relay 41, a revertive call signal actuated by said relay when energized, and a circuit to operate said relay closed by said relay 25 when energized through the terminals of the calling line associated with said automatic switching apparatus and the manually operated connection switch when said automatic switching apparatus makes connection with the calling line in response to a call.

18. In a telephone exchange system, the

- combination with a party telephone line, of a connecting circuit adapted to unite said line with other telephone lines, a signal controlling device, means, automatically operated only upon the connecting of said connecting circuit of said party line with itself in response to a call from a station on such line for any station on such line, to serially include said signal controlling device in said connecting circuit, and an operative circuit for said signal controlling device formed by said connecting circuit and calling line.
19. In a telephone exchange system, the combination with a party telephone line, of a connecting circuit, means for uniting one end of said connecting circuit with said line in response to a call, automatic switching apparatus for uniting the other end of said connecting circuit with telephone lines, a signal controlling device, means automatically operated upon the connection of said switching apparatus with the calling line in response to a call from a substation on said line for another substation on said line, for including said signal controlling device serially in said connecting circuit, and an operative circuit for said signal controlling device formed by said connecting circuit, switching apparatus and calling line.
20. In a telephone exchange system, the combination with a party telephone line, of a connecting circuit adapted to be united with said line, automatic switching apparatus adapted to unite said connecting circuit with telephone lines in response to calls from said first mentioned line, a signal controlling device, means, automatically operated when said switching apparatus unites with a calling line, for including said signal controlling device in the connecting circuit, and an operative circuit for said device completed when the switching apparatus unites with the calling line.
21. In a telephone exchange system, the combination with a party telephone line, of a connecting circuit, a connection switch for uniting said connecting circuit with said line, automatic switching apparatus adapted to unite said connecting circuit with telephone lines, a signal controlling device, means, operated upon the connection of said switching apparatus with said calling line in response to a call from such line, for including said signal controlling device serially in the connecting circuit, and an operative circuit for said device formed by said connecting circuit, switching apparatus, calling line and connection switch.
22. In a telephone exchange system, the combination with a party telephone line, of a connecting circuit adapted to be united with said line, automatic switching apparatus adapted to unite said connecting circuit with telephone lines, a signal control-

ling device and a source of current for operating the same, means, automatically operated when said switching apparatus unites with said calling line in response to a call therefrom, for including said signal controlling device and source of current in said circuit, and a circuit for said device and source formed by said connecting circuit, switching apparatus and calling line.

23. In a telephone exchange system, the combination with a party telephone line, of a connecting circuit adapted to be connected with said line, automatic switching apparatus adapted to connect said connecting circuit with telephone lines, said switching apparatus having a terminal connected with said calling line, a signal controlling device, means, automatically operated when said switching apparatus unites said connecting circuit with said calling line terminal in response to a call from such line, adapted to include said signal controlling device serially in said connecting circuit, and an operating circuit for said device formed by said connecting circuit, automatic switching apparatus, calling line terminal and calling line.

24. In a telephone exchange system, the combination with a party telephone line, of a connecting circuit adapted to be connected with said line, automatic switching apparatus adapted to connect said connecting circuit with telephone lines, said switching apparatus having a terminal connected with said calling line, a signal controlling device, a source of current, a conductor including said signal controlling device and source, means, automatically operated when said switching apparatus unites said connecting circuit with said calling line terminal in response to a call from such line, adapted to connect said conductor in series with said connecting circuit, and a circuit for said signal controlling device formed by said conductor, connecting circuit, switching apparatus, calling line terminal and calling line.

25. In a telephone exchange system, the combination with a party telephone line, of a connecting circuit adapted to be connected with said line, automatic switching apparatus adapted to connect said connecting circuit with telephone lines, said switching apparatus having a terminal connected with said calling line, a signal controlling device and a source of current, a loop conductor including said device and source, a relay adapted when energized to connect said loop conductor with said connecting circuit, a circuit for said relay automatically completed when said switching apparatus connects said connecting circuit with the terminal of the calling line in response to a call from such line, and a circuit for said signal controlling device completed by way of said

loop conductor, connecting circuit, switching apparatus, calling line terminal and calling line.

26. In a telephone exchange system, the combination with a party telephone line, of a connecting circuit adapted to be connected with said line, automatic switching apparatus adapted to connect said connecting circuit with telephone lines, said switching apparatus having a terminal connected with the calling line, a loop conductor having a signal controlling device and a source of alternating current therein, electromagnetic mechanism automatically operated when said switching device unites said connecting circuit with the terminal of the calling line in response to a call from such line, adapted to connect said loop conductor in series with said connecting circuit, and a circuit for said signal controlling device and source of alternating current completed by said loop conductor, connecting circuit, switching apparatus and calling line.

27. In a telephone exchange system, the combination with a party telephone line, of a connecting circuit, a connection switch for uniting said connecting circuit with said line, automatic switching apparatus adapted to connect said connecting circuit with telephone lines, a loop conductor having a source of current and a relay included therein, a relay adapted to connect said loop conductor with said connecting circuit, a circuit for said relay adapted to be completed when the switching apparatus unites with the calling line in response to a call from such line, a circuit for said first mentioned relay and its operating current completed by way of said loop conductor, connecting circuit, switching apparatus, calling line and connection switch, and a revertive call signal device controlled by said first mentioned relay.

28. In a telephone exchange system, the combination with a party telephone line, of a connecting circuit, a connection switch for uniting said connecting circuit with said line, switching apparatus adapted to connect said connecting circuit with telephone lines, a loop conductor having a source of current and a relay included therein, means, operated when said switching apparatus unites with the calling line in response to a call from such line, for connecting said loop conductor with said connecting circuit to complete an operating circuit for said relay, a supervisory signal associated with said connecting circuit, and means controlled by said relay for causing said supervisory signal to give a characteristic indication.

29. In a telephone exchange system, the combination with a party telephone line, of a connecting circuit, a connection switch for uniting said connecting circuit with said

line, automatic switching apparatus adapted to connect said connecting circuit with telephone lines, a loop conductor having a signal controlling relay therein, a transformer having its secondary winding included in said loop conductor, a source of alternating current connected in circuit with the primary winding of said transformer, and means, operated when said switching apparatus unites with the calling line in response to a call therefrom, for connecting said loop conductor serially with said connecting circuit, whereby a circuit is completed for current from said secondary winding of said transformer to operate said relay.

30. In a telephone exchange system, the combination with a party telephone line, of a connecting circuit, a connection switch for uniting said connecting circuit with said line, automatic switching apparatus for connecting said connecting circuit with telephone lines, a loop conductor having a source of current and a relay therein, means, operated when said switching apparatus unites with the calling line in response to a call therefrom, for momentarily connecting said loop conductor serially with said connecting circuit, whereby a circuit is completed from said relay and source of current by way of said conductor, switching apparatus, calling line and connection switch, a revertive call signal device operated by said relay when energized, and a locking circuit for said relay completed by itself when energized.

31. In a telephone exchange system, the combination with a party telephone line, of a connecting circuit, a connection switch for uniting said connecting circuit with said line, automatic switching apparatus for connecting said connecting circuit with telephone lines, a loop conductor having a source of current and a switching relay therein, means, operated when said switching apparatus unites with the calling line in response to a call therefrom, for momentarily connecting said loop conductor serially with said connecting circuit, whereby a circuit is completed for said switching relay and source of current by way of said loop conductor, switching apparatus, calling line and connection switch, a locking circuit for said switching relay, a supervisory signal controlling relay, and a circuit for said signal controlling relay having an interrupter therein completed by said switching relay when energized, and a locking circuit for said switching relay completed by itself when operated.

32. In a telephone exchange system, the combination with a party telephone line, of a connecting circuit, a connection switch for uniting said connecting circuit with said line, automatic switching apparatus for con-

necting said connecting circuit with telephone lines, a loop conductor having a source of current and a relay therein, means, operated when said switching apparatus unites with the calling line in response to a call therefrom for momentarily connecting said loop conductor serially with said connecting circuit, whereby a circuit is completed for said relay and source of current 10 by way of said loop conductor, connecting circuit, switching apparatus and connection switch, a supervisory signal controlling relay and a circuit for the last mentioned relay having an interrupter therein completed by said first mentioned relay when energized, a locking circuit for said first mentioned relay completed by itself when operated, and means controlled by the operator for opening said locking circuit.

33. In a telephone exchange system, the combination with a party telephone line, of a springjack connected with said line, a connecting circuit, a plug adapted to engage said jack to connect said connecting circuit with said line, automatic switching apparatus, a contact arm therefor adapted to be connected with said connecting circuit, said switching apparatus having terminals adapted to be connected with said arm, said 25 switching apparatus being adapted to bring said contact arm into contact with any one of said terminals in response to a call therefor, one of said terminals being connected with said springjack, a loop conductor having a source of current and a revertive call signal controlling device included therein, a relay adapted to connect said loop conductor with said connecting circuit, and a circuit for said relay adapted to be automatically 30 completed when the contact arm of said switching apparatus engages the terminal of the called line; whereby when the contact arm of said switching apparatus engages the terminal of a calling line in response to a call therefrom a circuit is completed for 35 said signal controlling device and a source of current.

34. In a telephone exchange system, the combination with a party telephone line, of a connecting circuit, a resistance associated with said connecting circuit arranged to be connected with said line when calling, a shunt around said resistance and means for momentarily opening said shunt.

35. In a telephone exchange system, the combination with a party telephone line, of a connecting circuit, a resistance associated with said connecting circuit arranged to be connected to said line when calling, a shunt 40 around said resistance, a supervisory device in series with said resistance and means for momentarily opening said shunt.

36. In a telephone exchange system, the combination with a party telephone line, of

a connecting circuit, test means associated therewith, a resistance associated with said connecting circuit adapted to be connected to the calling line, a shunt around said resistance and means for opening said shunt when the called line is tested.

37. In a telephone exchange system, the combination with a party telephone line having multiple terminals, of a connecting circuit adapted to be united therewith, means associated with said connecting circuit for placing a test guard upon said party line, a signal device and a circuit for said signal device including said multiple terminals at both ends of said connecting circuit, and means for removing said test guard and closing the circuit of said signal device.

38. In a telephone exchange system, the combination with a party telephone line having multiple terminals, of a connecting circuit adapted to be united therewith, means associated with said connecting circuit for placing a test guard upon said party line, a signal device including a talking conductor and said multiple terminals at both ends of said connecting circuit, and means for removing said test guard and closing the circuit of said signal device.

39. In a telephone system, the combination with a multi-party line, of a switching circuit extending between two differently located switching devices and adapted to be connected to said line at one of the switching devices when said line is calling and at the other switching device when to be called, and means including a supervising indicator which is also arranged and adapted automatically to indicate a reverted call at said last named switching device.

40. In a telephone system, the combination with a multi-party line, of a switching circuit extending between two differently located switching devices and adapted to be connected to said line at one of the switching devices when said line is calling and at the other switching device when to be called, and means including a supervising indicator which is also arranged and adapted to automatically indicate a reverted call at said last named switching device.

41. In a telephone system, the combination with a multi-party line, of a switching circuit extending between two differently located switch boards and adapted to be connected to said line at one of said switch boards when said line is calling and at the other switch board when to be called, and means including a supervising indicator which is also arranged and adapted automatically to indicate a reverted call at said last named switch board.

42. In a telephone system, the combination with a multi-party line, of a switching circuit extending between two differently

located switch boards and adapted to be connected to said line at one of said switch boards when said line is calling and at the other switch board when to be called, and means including a supervising indicator which is also arranged and adapted to automatically indicate a reverted call at said last named switch board.

43. In a telephone system, the combination with a line, of a switching circuit, automatically operated means adapted to connect said line with one end of said switching circuit, means for connecting the other end of said switching circuit with another circuit, and means including a supervising indicator which is also arranged and adapted to indicate at said last named end of the switching circuit whether said circuit is connected to said line.

44. In a telephone system, the combination with a multi-party line, of a switching circuit, automatically operated means for connecting one end of said switching circuit with said line, manually operated means for connecting the other end of said switching circuit with another circuit, and means including a supervising indicator which is also arranged and adapted automatically to indicate a reverted call.

45. In a telephone system, the combination with switching circuits extending between two differently located switching devices and adapted to be connected with a calling line at the one switching device and with a line to be called at the other device of means including an indicator adapted to indicate at one of said devices that a calling line is connected or is going to be connected to said switching circuit, and means including the same indicator as that of the foregoing means for supervision of the call.

46. In a telephone system, the combination with a switching circuit extending between two differently located switching de-

vices and adapted to be connected with a multi-party line at the one device when said line is calling and at the other device when to be called, of means including an indicator for supervising the call, and means including the same indicator adapted to indicate at one of said devices a reverted call.

47. In a telephone system, a telephone line, a link circuit, a plug terminal for one end of said link circuit, and an automatic switch for the other end, and a visual signal at said link circuit to indicate to the operator thereat when both ends of said link circuit are simultaneously connected to said line.

48. In a telephone system, the combination with a telephone line, of a link circuit, multiplied terminals for said line, a plug and an automatic switch for said link circuit, and a visual signal at said link circuit to indicate to the operator thereat when said plug and said automatic switch are simultaneously connected to different ones of said multiplied terminals.

49. In a telephone exchange system, a line, answering and calling terminals therefor, a connecting circuit, means for extending one end of said circuit to the answering terminal, means for extending the other end of said circuit to the calling terminal, a busy test circuit for said line established upon the extension of said circuit to its answering terminal, a signal, a relay for controlling said circuit, and another relay provided in said connecting circuit for controlling said relay and signal.

In witness whereof, I hereunto subscribe my name this 28th day of January, A. D. 1907.

ALBERT M. BULLARD.

Witnesses:

GEORGE A. HAMILTON,
WILLIAM F. LUTTER.
